(57) **CLAIM**

The ornamental design for a toy car chassis, as shown and described.

DESCRIPTION

FIG. 1 is a perspective view of a toy car chassis, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a sectional view taken along line 9-9 from FIG. 6;

FIG. 10 is an exploded perspective view thereof; and,

FIG. 11 is an exploded top view thereof.

All the broken lines in the drawings depict portions of the toy car chassis that form no part of the claimed design.

1 Claim, 11 Drawing Sheets
